UNITED STATES PATENT OFFICE.

MARTIN CHRISTENSEN, OF RACINE, WISCONSIN, ASSIGNOR TO CHRISTENSEN MACHINE CO., OF RACINE, WISCONSIN, A CORPORATION OF WISCONSIN.

BOOK-STITCHING MACHINE.

Application filed December 13, 1919. Serial No. 344,697.

To all whom it may concern:

Be it known that I, MARTIN CHRISTENSEN, a citizen of the United States, and resident of Racine, in the county of Racine and State of Wisconsin, have invented new and useful Improvements in Book-Stitching Machines, of which the following is a description, reference being had to the accompanying drawings, which are a part of this specification.

The present invention relates to certain new and useful improvements in book stitching machines and refers more particularly to a front delivery bearing member used in connection therewith.

The book stitching machines now in general use do not discharge a book until after the second stroke after the book has been stitched, which means that when a twenty inch stroke is being employed it is necessary that the book be moved forty inches after being stitched. This necessitates an unusually long machine whereas if the book could be discharged at the end of the very next stroke after being stitched, the machine would be shortened by twenty inches and thus considerably reduce the cost of the machine.

Hence, with the above and other features in mind my invention has for one object to provide means whereby the book is discharged at the end of the very next stroke after being stitched, or after the book has passed the center of the last stitcher.

Another more specific object of this invention is to provide an out-set support for the delivery roll shafts whereby the stitcher mechanism may be positioned there adjacent and a book delivered from the machine at the end of the very next stroke after being stitched.

A still further object of the present invention is to provide an out-set bearing for the purpose described in which a book will be discharged over the large delivery roll shaft bearing.

With the above and other objects in view, which will appear as the description proceeds my invention resides in the novel construction, combination and arrangements of parts substantially as hereinafter described and more particularly defined by the appended claims it being understood that such changes in the precise embodiment of

the herein described invention may be made as come within the scope of the claims.

In the accompanying drawing I have illustrated one complete example of the physical embodiment of my invention constructed according to the best mode I have so far devised for the practical application of the principles thereof and in which:

Figure 1 is a front plan view of a portion of a book stitching machine equipped with my novel form of front delivery bearing member,

Figure 2 is a perspective view of my novel form of front delivery bearing member detached from the stitching machine,

Figure 3 is a view similar to Figure 1 of a slightly modified form of construction, and

Figure 4 is a fragmentary sectional view taken through the machine on the plane of line 4—4 of Figure 1, said view illustrating means for removing the signature from the saddle.

Referring now more particularly to the drawing the numeral 5 designates a feed table of a book stitching machine along which series or groups of signatures 6 are fed to be stitched by suitable stitchers 7 co-operating with clinchers 8 and then be delivered from the machine by means of a plurality of delivery rolls and belts to be later described. For a further description and illustration of the type of machine referred to, attention is called to United States Patent #1,028,708 which shows a book stitching machine.

One objection to the machines now in general use is that by reason of the stitcher member disposed adjacent the delivery rolls being spaced therefrom owing to the construction of the bearing support for the delivery roll shafts, a group of signatures or book after being stitched can not be delivered until the end of the second stroke of the machine. I have overcome this objection by a novel form of bearing member 9 which permits the positioning of a stitcher 7 juxtapose the delivery mechanism so that a book after being stitched may be delivered at the end of the very next stroke of the feed finger carrying bar 26 of the feed mechanism.

The feed mechanism may be of any desired construction, but is illustrated in the accompanying drawing as comprising a feed bar 27, slidably mounted in one face of the saddle 5, see Figure 4, and

signature engaging fingers 28 carried by the bar 26 for binding the signatures between them and bar 27 when said bars are conjointly moved toward the delivery end of the machine by suitable means, not shown.

My novel form of bearing member consists of a securing arm 10 adapted to be secured to the stitching machine frame 11 by suitable securing means (not shown) passed through apertures 12 and having extended therefrom the bearings for the delivery roll shafts. Formed at the outer end of the bracket member 10 is a bearing 13 for receiving the lower small delivery roll shaft and extending upwardly and outwardly therefrom near its outer end 14 is a web or offset support 15 having an upper small delivery roll shaft bearing 16 formed on its outer end. As best shown in Figure 2, the web 15 is secured to the bearing 16 near its outer end 17, whereby a recess or space 18 is formed between the bearings 13 and 16 so that the stitcher 7 may be moved therein, as depicted in Figure 1.

A downwardly and inwardly extending off-set web or support 19 extends from the inner end 20 of the bearing 16 and has a large delivery roll shaft bearing 21 formed at its lower end, said bearing 21 projecting outwardly from the web 19 to provide a space 22 between the bearings 16 and 21, for the reasons to be later described.

As best shown in Figure 1 a lower small delivery roll shaft 13' has its inner end mounted within the bearing 13; an upper small delivery roll shaft 16' has its inner end mounted in bearing 16; and a large delivery roll shaft 21' has its inner end mounted within bearing 21. Mounted upon the shafts 13', 16' and 21' are a plurality of sets of rolls, each having a delivery belt 23, trained thereabout and said belts and rolls pick up the signatures after being stitched and deliver or discharge the same from the stitching machine.

The completed signatures are delivered to the belts 23 in any desired manner, as for instance, by a vertically movable plate 29 positioned within saddle 5 at its apex and adapted to engage the signatures at their folds and project them between the belts and the rolls on shaft 21'. The plate 29 is operated, in the present instance, by rods 30 having their upper ends secured to said plate and their lower ends engageable with cams 31 mounted on a shaft 32 in connection with the machine drive, not shown. As this delivery mechanism forms no important feature of this invention except that the construction of the bearing member 9 permits the same to engage the book at the end of the very next stroke after being stitched further detailed description is thought unnecessary.

A bearing 24 is formed on the top inner end of the bracket member 10 for receiving the idle delivery roll shaft, and a bearing 25 is formed on the web 19 for receiving the guide shank bar 26, as will be understood the bearing member 9 is cast in a single piece and is capable of production at a very low cost, all things considered.

In operation, the signature 6 in position to be stitched is positioned beneath the delivery roll shafts at the end of the stroke immediately after the stitching mechanism has operated and by reason of the peculiar construction of the bearing member 9 the inner end of the book would then be disposed in line with the bearings 16 and 21 but will be just outwardly of the web 19 so that the delivery belts 23 may pick the same up from off the feed table and discharge it from the machine. When the signature is discharged from the stitching machine its inner end passes the lower most bearing 21 between the upper bearing 16 as designated in dotted line in Figure 1.

In Figure 3 I have shown a slightly modified form of construction of my improved bearing member in which the web member 19 is positioned a great distance from web 15 depicted in Figures 1 and 2 whereby the bearing member is so positioned that the signatures 6 may be discharged from the machine after the inner end thereof has passed the center of the last stitcher 7. This structure permits the discharge of the signatures before the end of the next stroke after the same has been stitched as will be obvious.

What I claim as my invention is:

1. In a book stitching machine, the combination of a stitcher, a signature support, means for feeding signatures along said support to said stitcher to be stitched and then away from said stitcher after the stitching operation, delivery rolls, delivery roll shafts carrying said rolls, a bearing member for said roll shafts so arranged that the stitcher may operate upon a signature adjacent the ends of said shafts, and means for removing the completed signatures from the signature support immediately after they have been fed past the center of the stitcher by said feeding means and presenting them to the delivery rolls.

2. In a book stitching machine, the combination of a stitcher, a saddle traversing the stitcher, means for feeding the signatures along the saddle and means for removing completed signatures from the saddle immediately after they have been fed past the center of the stitcher by said feeding means.

In testimony whereof, I affix my signature.

MARTIN CHRISTENSEN,
